EXPANDABLE PLUG WRENCH

Charles Byron Wahl, Philadelphia, Pa., assignor to The United Gas Improvement Company, Philadelphia, Pa., a corporation of Pennsylvania

Application April 20, 1934, Serial No. 721,524

8 Claims. (Cl. 81—53)

The present invention relates to apparatus for stopping gas service pipes by the insertion in a gas service pipe of an expandable plug.

Such plugs are used among other purposes for preventing the theft of gas from services which are presumably inactive and shut off. For this purpose, a special plug has been developed which may be inserted a considerable distance into the pipe, usually about 10 or 12 inches from the head of the service, by means of a long wrench, and expanded, stopping off the gas. The plug and the wrench co-operate in such a manner that the plug may not be inserted or removed without the use of the special wrench.

The previously known apparatus has certain disadvantages, the obviating of which is the principal object of the present invention. These disadvantages and the advantages of the invention of this application may best be pointed out in connection with the description of the attached drawing which forms a part of this specification and which shows the present and the improved apparatus, and in which:

Fig. 1 shows a side elevation, with parts broken away, of a form of the improved wrench of the present application for positioning, expanding and removing the plug of Figs. 2 and 3.

Fig. 2 shows a side elevation of the expandable plug.

Fig. 3 shows an end elevation of the plug of Fig. 2.

Fig. 4 is a side elevation of the tip of the sleeve.

Fig. 5 is an end view of the tip of the sleeve.

Fig. 6 is a side elevation of the tip of the barrel.

Fig. 7 is a side elevation of the tip of the head.

Fig. 8 is an end view of the tip of the head.

Referring to Figs. 2 and 3, 1 indicates a tapered rubber stopper provided with a central bore, through which is passed the threaded-bolt 2.

40 The stopper is held between the washers 3 and 4 which have central holes arranged to fit loosely around the bolt 2. The sliding nut 5 is not threaded and also fits loosely around the bolt and is provided with the pin 6 which extends into the slot 7 in the bolt 2. 8 is a threaded-nut provided with the socket 9.

45 Referring to Figs. 1, and 4 through 8, 10 generally indicates the body or barrel of the wrench, in which the head 11 may be turned by the handle 12 and the stem 13. The head 11 is provided with the pin 14 adapted to engage the socket 9 in the plug (Figs. 2 and 3). The barrel 10 is provided with the slotted socket 15 intended to engage and retain the pin 6 of the plug. The stem 13 has attached to it a collar such as 16, which is engaged

by a spring such as 17, which presses the head 11 against the end of the plug, when the plug is inserted in the wrench.

In operation, with the handle drawn back compressing the spring 17 and retracting the head 11 within the barrel of the wrench, the end of the plug is inserted in the barrel, the pin 6 passing through the straight portion of the socket slot 15. The plug is then turned, engaging the pin in one of the wings of the socket, preferably the upper wing in the view of the wrench shown in Fig. 1. The handle is then released and turned until the pin 14 is aligned with and enters the socket 9 in the plug. The pressure of the spring 17 holds the head 11 against the end of the plug, retaining the pin 6 in the socket wing.

The plug is then inserted through the head of the service to the desired distance into the pipe, usually 10 or 12 inches. Then, holding the barrel of the wrench stationary, the handle is turned clockwise, turning the nut 8 by means of the head 11, pin 14 and socket 9. The bolt 2 of the plug is held from turning by the pin 6, which is held in socket 15 and which extends into the slot 7 in the bolt. Turning the nut 8, with the bolt held stationary, compresses the rubber stopper 1 longitudinally and causes it to expand radially, stopping the service and preventing any flow or leakage of gas past the plug. Head 11 is provided with a central cavity 18, to allow entrance of the end of bolt 2 exposed by the screwing-up of nut 8.

The handle 12 of the wrench is then withdrawn, releasing the pin 14, and the barrel of the wrench is turned to align the straight portion of the socket 15 with the pin 6 and the wrench withdrawn, leaving the plug expanded well within the service.

In removing the plug, the wrench is inserted in the pipe until it encounters the end of the plug. With the handle, and hence the head 11, pulled back, the barrel is turned until the pin 6 is aligned with the straight portion of the socket 15; the wrench is then pushed farther in, the sides of the straight portion of the socket 15 passing on either side of the pin 6. The barrel is then turned to position the pin in the lower wing of the socket 15 in the view of the wrench shown in Fig. 1; the handle is here released and turned until the pin 14 engages and enters the socket 9 of the plug. The handle is then turned counter-clockwise, unscrewing the nut 8 and releasing the pressure upon the rubber stopper 1, which resumes its unexpanded position, in which condition the plug may be withdrawn from the pipe.

The apparatus described has a decided dis-

advantage. If, when the plug is inserted in the barrel of the wrench, the pin 6 is positioned in the wrong wing of the socket 15 in expanding the plug, or if the pin is in the correct wing but the wrench is inadvertently turned the wrong direction, the pin in the turning movement may become aligned with the straight portion of the socket slot 15, and, due to the action of the spring 17, the plug may be forced out of the barrel of the wrench in unexpanded condition and shot into the portion of the pipe ahead of the wrench. It is then very difficult to recover, as it merely moves farther into the pipe when one tries to engage it with the wrench.

15 The same trouble may occur in removing the plug after rubber stopper has been released. To overcome this difficulty, I have added to the above-described device as follows: 19 is a sleeve which fits loosely around the barrel 10 and which is provided with a screw-pin 20, which is screwed into a threaded hole in the sleeve and extends within a short slot 21 cut in the barrel 10. The sleeve 19 is provided with a key 22, which is in sliding engagement with the straight portion of socket slot 15 on the barrel 10 and with a rearward extension of the straight portion of that slot indicated 23. A spring 24 is provided, which encircles the barrel 10 and abuts an internal shoulder of the sleeve 19 at 25 and an external shoulder on the barrel 10 at 26.

30 When the plug is to be inserted in the barrel of the wrench, the operation is as has been described, except that, first, the sleeve 19 is slid back, compressing the spring 24, the screw-pin 20 sliding in the slot 21 and the key 22 sliding into the extension 23 of the socket slot 15. The parts are arranged so that the sleeve may be withdrawn sufficiently to enable the key 22 to be withdrawn entirely into the extension slot 23, permitting the pin 6 of the plug to be positioned in either wing of the socket 15. The sleeve is then released and the spring 24 moves the sleeve 19 forward, the key 22 sliding into the position shown in Fig. 1 and locking the pin 6 within the wing of slot 15, from which it will not be released no matter how the wrench is turned, and there is no danger of the plug being shot into the pipe ahead of the wrench. The slot 21 and the pin 20 serve to retain the sleeve and limit its travel along the barrel of the wrench.

50 In this arrangement, it is not necessary to position the pin 6 of the plug in one particular wing of the socket 15 when expanding the plug in the pipe and in the other wing when removing the plug from the pipe, but the pin may be positioned in either wing for either operation.

I do not intend to be limited save as the scope of the prior art and of the attached claims may require.

60 I claim:

1. A wrench for expandable pipe plugs including in combination a barrel member, a retractable wrench-head enclosed by said barrel member, said wrench-head being provided with means for engaging and turning a tightening member on a plug and said barrel being provided with a slotted socket for engaging a radial pin on said plug, said slotted socket including a longitudinal slot having one or more lateral wings, and retractable locking means slideable in said longitudinal slot in the barrel and adapted to lock said radial pin of the plug within a lateral wing of said socket when positioned therein.

75 2. A wrench for expandable pipe plugs including in combination a barrel member, are tract-

able wrench-head enclosed by said barrel member, said wrench-head being provided with means for engaging and turning a tightening member on a plug and said barrel being provided with a slotted socket for engaging a radial pin on said plug, said slotted socket including a longitudinal slot having one or more lateral wings, retractable locking means slideable in said longitudinal slot in the barrel and adapted to lock said radial pin of the plug within a lateral wing of said socket when positioned therein, and spring means for moving said retractable locking means into the locking position.

3. A wrench for expandable pipe plugs including in combination a barrel member, a retractable wrench-head enclosed by said barrel member, said wrench-head being provided with means for engaging and turning a tightening member on a plug and said barrel being provided with a slotted socket for engaging a radial pin on said plug, said slotted socket including a longitudinal slot having one or more lateral wings, retractable locking means slideable in said longitudinal slot in the barrel and adapted to lock said radial pin of the plug within a lateral wing of said socket when positioned therein, spring means for moving said retractable locking means into locking position, and means associated with the retractable locking means and the barrel for limiting movement of said locking means.

4. A wrench for expandable pipe plugs including in combination a barrel, a retractable wrench-head enclosed by said barrel, said wrench-head provided with means for engaging and turning a tightening member of a plug, said barrel being provided with a slotted socket for engaging a pin member on the plug, said slotted socket comprising a longitudinal slot having one or more lateral wings, and a retractable sleeve enclosing a portion of the wrench barrel and provided with means slideable in the longitudinal socket slot in the barrel and adapted to lock the pin of the plug within a lateral wing of said socket slot.

45 5. A wrench for expandable pipe plugs including in combination a barrel, a retractable wrench-head enclosed by said barrel, said wrench-head being provided with means for engaging and turning a tightening member of a plug, said barrel being provided with a slotted socket for engaging a pin member on the plug, said slotted socket comprising a longitudinal slot having one or more lateral wings, and a retractable sleeve enclosing a portion of the wrench barrel and provided with an internal key slideable in the longitudinal socket slot in the barrel and adapted to lock the pin of the plug within a lateral wing of said socket slot.

50 6. A wrench for expandable pipe plugs including in combination a barrel, a retractable wrench-head enclosed by said barrel, said wrench-head being provided with means for engaging and turning a tightening member of a plug, said barrel being provided with a slotted socket for engaging a pin member on the plug, said slotted socket comprising a longitudinal slot having one or more lateral wings, a retractable sleeve enclosing a portion of the wrench barrel and provided with an internal key slideable in the longitudinal socket slot in the barrel and adapted to lock the pin of the plug within a lateral wing of said socket slot, and spring means for moving said sleeve into the locking position.

55 7. A wrench for expandable pipe plugs including in combination a barrel, a retractable wrench-head enclosed by said barrel, said wrench-head being provided with means for engaging and turn-

ing a tightening member of a plug, said barrel being provided with a slotted socket for engaging a pin member on the plug, said slotted socket comprising a longitudinal slot having one or more lateral wings, a retractable sleeve enclosing a portion of the wrench barrel and provided with an internal key slideable in the longitudinal socket slot in the barrel and adapted to lock the pin of the plug within a lateral wing of said socket slot, 5 spring means for moving said sleeve into the lock-

ing position, and means associated with the sleeve and barrel for limiting the movement of the sleeve.

8. In a wrench for expandable pipe plugs, a barrel having a slot with lateral extensions in the wall of the barrel, and an element mounted on said barrel and having thereon a lug slideable in said slot to open and close communication between said lateral extensions and said slot. 5
